(57) **CLAIM**

The ornamental design for a mobile payment cell phone, as shown and described.

DESCRIPTION

FIG. 1 is a first perspective view of embodiment 1 of a mobile payment cell phone when the phone is not used; FIG. 2 is a second perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; FIG. 9 is another perspective view of embodiment 1 of a mobile payment cell phone shown in a usage state when the phone is used. FIG. 10 is a first perspective view of embodiment 2 of a mobile payment cell phone when the phone is not used; FIG. 11 is a second perspective view thereof; FIG. 12 is a front view thereof; FIG. 13 is a rear view thereof; FIG. 14 is a left side view thereof; FIG. 15 is a right side view thereof; FIG. 16 is a top view thereof; FIG. 17 is a bottom view thereof; and, FIG. 18 is another perspective view of embodiment 2 of a mobile payment cell phone shown in a usage state when the phone is used.

The broken lines in the figures depict portions of the mobile payment cell phone that form no part of the claimed design.
